UNITED STATES PATENT OFFICE.

ROBERT W. COOPER, OF DAYTON, KENTUCKY, AND FRANK A. LEE AND RAY J. MEYER, OF CINCINNATI, OHIO; SAID COOPER AND SAID LEE ASSIGNEES TO THE JOHN CHURCH COMPANY, OF CINCINNATI, OHIO, A CORPORATION OF OHIO.

PNEUMATIC PIANO-ACTION.

1,133,793.

Specification of Letters Patent. Patented Mar. 30, 1915.

Application filed July 7, 1913. Serial No. 777,629.

To all whom it may concern:

Be it known that we, ROBERT W. COOPER, a citizen of the United States, and a resident of the city of Dayton, in the county of

5 Campbell and State of Kentucky, and FRANK A. LEE and RAY J. MEYER, citizens of the United States, and residents of the city of Cincinnati, in the county of Hamilton and State of Ohio, have invented certain new and useful Improvements in Pneumatic Piano-Actions, of which the following is a full, clear, and exact description, reference being had to the accompanying drawings, forming part of this specification.

10 As is well known to persons skilled in the art, the necessary mechanical relation between the piano action and the pneumatic power action is achieved by means of what is called generally a striking pneumatic, in 20 the general form of a small bellows. This statement applies to any form of musical instruments which are mechanically operable, but particularly to pianos as aforesaid. It has been found that the contact of the 25 pneumatic key aforesaid with the piano action produces a "touch," the principal characteristics of which are excessive sharpness, crispness and hardness, so that the line of demarcation between the sort of piano 30 "touch" provided through pneumatic mechanism and through the finger operating upon the keyboard of the piano has always been very marked. In order to overcome this acknowledged defect, we have provided

35 a certain construction and arrangement of parts as hereinafter specifically pointed out and claimed, whereby the function of the so-called pneumatic key or power pneumatic as a counterpart of the finger key is preserved 40 through a somewhat analogous form of that part of the piano action known as the wippen, whereby a rounded contact between parts actuated by said pneumatic and the wippen of the piano action is provided, to 45 approach as near as possible in effect, the contact in the mechanical operation of the piano action when actuated by the finger through the ordinary keyboard.

In the drawings, Figure 1 is a side elevation of our device. Fig. 2 is an end view of the complementary wippen flange and connection. Fig. 3 is a similar view at the other end of the wippen showing the connections with its sticker. Fig. 4 is a side

elevation of the wippen construction showing the novel contact feature. Fig. 5 is an enlarged perspective of the complementary wippen.

1 is a power pneumatic with the extension 2 on its movable member to actuate the piano action, and 3 is the key of a piano. The usual construction of upright piano action is followed in connection with the key of the piano. As illustrated in Fig. 2, there is the abstract 4, with abstract lever 5 and flange 6. The abstract has at its end the capstan screw 7, and has the ordinary connection with the wippen 8. There is the spoon 9, located outside of the wippen flange 10, the flange mounted on the middle action rail 11. Mounted on the wippen is the jack 12, with its flange 13 and its spring 14 bearing on the wippen. The back check 15 is mounted on the wippen, and also the bridle wire 16. This action, as detailed, 70 covers the usual construction and arrangement of parts for tripping the hammer (not shown) of the ordinary upright piano. For the pneumatic action, we utilize the same wippen and the parts mounted thereon, but provide a lever, connect it with the movable member of the pneumatic and preferably by our novel contact means impart the movement of the lever to the direct wippen. A rod 17 is provided, upwardly 75 extending, and suitably attached at 18 to the extension 2 of the pneumatic movable member.

80 Mounted on an additional middle action rail 24, is the lever 21. This mounting is by 90 the usual flange 25 with bifurcated end into which the lever end is placed, and the swinging connection between the two secured by the pin 22. At the end of the lever opposite its flange is a depending knob 19, 95 through a hole in which is inserted the hook 20 on the upper end of the rod 17. The rod thus acts as a push rod between the pneumatic and the lever 21. The wippen extends in from the jack and on its under side 100 is provided preferably with the rounded contact knob 26. A rounded contact knob 23 is provided on the lever 21, and the parts so arranged that these two rounded knobs coincide.

105 The operation is simple. When motion is imparted to the rod 17, it raises the lever to which it is attached. This lever then raises

the wippen of the piano action, located directly above it, and the wippen then raises the jack of the action. The proper contact, complete and regular throughout, which has been found necessary in this connection is best maintained by the rounded surfaces of the two contact knobs. One rounded surface, raised against the other rounded one, gives the required continuous and precise movement necessary to obtain the proper tripping of the hammer of the action, and thus to approximate the human touch with the mechanical player. The rounded contact is, however, the preferred form.

Having thus described our invention, what we claim as new and desire to secure by Letters Patent, is:—

1. In a combination key and pneumatic power piano action, a pivoted wippen for the key action, a pivoted lever positioned to

contact therewith, connection from the lever to the pneumatic power parts, a rounded knob on the wippen and a rounded knob on the lever at the point of contact between them, for the purpose described.

25

2. In a combination key and pneumatic power piano action, a pivoted wippen for the key action, a pivoted lever positioned to contact therewith, connection from the lever to the pneumatic power parts, a depending rounded knob on the wippen and an upwardly extending rounded knob on the lever at the point of contact between them, for the purpose described.
